JACK MECHANISM HAVING AN INTERNAL LOCKING MEANS

Frank S. Pearne, Alhambra, Calif., assignor to Regent
Jack Mfg. Co., Inc., Downey, Calif., a corporation of
California

Filed Dec. 29, 1959, Ser. No. 862,648
11 Claims. (Cl. 60—52)

This invention relates to a jack mechanism having an internal locking means, and, more particularly, to an improved hydraulic jack structure having an extensible ram and an internal locking means for releasably locking the ram in an extended position.

The invention is particularly concerned with hydraulic jacks which are required to be repeatedly and quickly extended to support a load, locked in the extended position, and then unlocked and retracted. In order to satisfy these requirements, I have devised unique internal locking means for the ram which can be manipulated in a facile manner to quickly lock the ram so that it may support a load, and then to unlock the ram in an equally easy fashion whereby the ram can be retracted. My novel jack mechanism also includes means to automatically retract the ram when the ram has been unlocked. For illustrative purposes, the invention has been shown and described in conjunction with both a leveling jack and an aircraft tripod jack, however, it is to be understood that the invention may be embodied in many other types of jacks.

Conventional jack constructions commonly employ a locknut which is threaded on the extended portion of the ram into abutment or engagement with the outer shell of the jack to hold the ram in its extended position. This type of construction possesses several disadvantages, the most significant of which is the relatively long time which is required to lock and unlock the ram. Another disadvantage is that, when a jack employing this form of locking means is used out-of-doors, water frequently runs down the threads of the locknut and enters the cylinder thereby seriously affecting the operation of the jack.

With specific regard to the construction of leveling jacks such as are used on load-supporting vehicles to level the vehicle and to raise the load from the wheels when the vehicle is stationary, the forms of constructions heretofore known possess additional disadvantages over and above the ram locking means. One major objection in the case of leveling jacks permanently mounted on a vehicle is that, commonly, no means are provided for automatically retracting the ram when it is unlocked. As a result, the ram is often left at least partially extended through inadvertence of the operator when the vehicle is moved, and, hence, the ram is frequently damaged when the vehicle passes over a slight ground rise or the like. Another disadvantage is that the fluid supply or reservoir for the jacks is often separate from the main body or shell thereby making the entire assembly extremely unwieldy and difficult to install in the available space.

An object of the present invention is to provide a jack mechanism with internal ram locking means which may be operated in a facile manner to lock the ram in an extended position and then to quickly unlock the ram when the latter element is to be retracted.

Another object is to provide a jack mechanism having internal ram locking means of the type described with means for automatically retracting the unlocked ram.

Still another object is to provide a jack mechanism with internal ram locking means whereby water encountered in outdoor use is prevented from entering the cylinder of the jack.

Another more specific object of the invention is to pro-

2

vide a unique hydraulic leveling jack mechanism having internal ram locking means and a self-contained fluid reservoir.

Other objects and advantages of the invention will become more readily apparent when the same is considered in connection with the following detailed description and the accompanying drawings wherein:

FIGURE 1 is a schematic side elevation of a dolly having attached leveling jacks constructed in accordance with my invention.

FIGURE 2 is a side view of my novel leveling jack construction.

FIGURE 3 is a vertical section of the leveling jack shown in FIG. 2 showing one embodiment of the internal ram locking means.

FIGURE 4 is a view similar to FIG. 3 but showing the ram in an extended and locked position.

FIGURE 5 is a horizontal sectional view taken through the jack near the top thereof along the line 5—5 of FIG. 3.

FIGURE 6 is an enlarged vertical sectional view of a portion of the jack showing the piston in an upstroke and showing a fluid by-pass opening for retracting the jack.

FIGURE 7 is a side elevational view of a portion of the internal locking means for the ram.

FIGURE 8 is a fragmentary side elevational view showing another portion of the internal locking means.

FIGURE 9 is a fragmentary side elevation showing the assembled locking mechanism.

FIGURE 10 is a fragmentary side elevation, partly in section, of a leveling jack having a modified locking mechanism.

FIGURE 11 is a horizontal sectional view taken through the jack of FIG. 10 near the top thereof along the line 11—11 of FIG. 10.

FIGURE 12 is a side view of an aircraft tripod jack embodying the locking mechanism shown in FIGS. 10 and 11.

FIGURE 13 is a vertical sectional view of the jack shown in FIG. 12.

FIGURE 14 is a horizontal sectional view taken through the jack of FIG. 12 near the top thereof along the line 14—14 of FIG. 13.

Referring now to the drawings, the apparatus embodying my invention may be in the form of a leveling jack which is used to stabilize and level a load relative to the ground or other supporting surface. As shown diagrammatically in FIG. 1, four such jacks 20 may be arranged at the corners of a missile dolly D adjacent each wheel.

When the dolly is being moved, the jacks are maintained above the lower wheel surfaces, and when the dolly is stationary, as in a firing position or a storage position, the jacks are lowered or extended to raise the weight of the loaded dolly from the wheels. As will hereinafter be

discussed in more detail, the construction of the jacks is such that they are automatically fully retracted from their extended, load-bearing position, thereby eliminating the hazard of the jacks being inadvertently left in a partially extended position and damaged when the dolly is moved over a slight ground rise. My novel leveling jack is not limited, of course, to use on vehicles since it is equally well adapted to be used in conjunction with any support equipment.

Referring next to FIGS. 2 through 9, there is shown in detail a leveling jack construction embodying one form of my invention. The principal components of the illustrated jack include an outer shell 21 having a load carrying ring 22 welded or otherwise secured thereto, a ram 23, a main shaft 24, a pump cylinder 25, and a piston 26, the latter four components being concentrically nested within the shell. A foot pad 27 is connected to the ram and is adapted to be pushed by the foot of the operator

into initial contact with the ground, as shown in dot-dash outline in FIG. 2, while a handle 28, operatively connected to the piston 26, is adapted to be actuated by the hand of the operator to apply hydraulic pressure to the extended ram.

The outer shell 21 preferably is in the form of an elongated, hollow, open-ended cylinder, and includes a collar 33 permanently secured to the inner surface of the shell at its bottom end. The collar includes an inner groove 34 which receives an O-ring 35, while the inner surface of the upper end of the shell is notched to receive a locking ring 36. The load ring 22 may be fastened to the outer periphery of the shell 21 approximately one-third of the distance from the bottom toward the top of the shell.

The ram 23 is also in the form of a hollow cylinder, and has a diameter such that it may be concentrically nested in a position contiguous to the inner surface of collar 33 with the wall of the ram spaced inwardly from the shell 21. A helical compression spring 49, positioned in the space between the ram and shell, constantly urges the ram to a retracted position wherein the upper end of the ram 23 is spaced below the upper end of the shell. The lower end of the ram is plugged by a ram base 41 which has a threaded recess 42 in its bottom, and the foot pad 27 is secured to this ram base by means of a bolt 43 which is threaded into the recess 42. The head of the bolt 43 is pivotally anchored within the pad by a washer 44, the pivotal connection serving to permit the pad to engage uneven supporting surfaces.

As shown most clearly in FIG. 5, the main shaft 24 is square in transverse section and has a square bore, there being a shaft base 50 and a shaft head 45 integrally joined to the bottom and top, respectively, of the main shaft. The diameter of the shaft base 50 is equal to that of the ram base 41 and is greater than the width of the main shaft, whereby the walls of the shaft are spaced inwardly from the cylindrical wall of the ram. The diameter of the main shaft head is equal to the inner diameter of shell 21 so that, in its assembled position, the main shaft head 45 and attached shaft will be locked against upward movement by the lock ring 36 which is seated in a circular seat 51 cut in the head. The outer shell 21, shaft head 45 and shaft base 50 define a fluid reservoir 49 from which fluid is drawn during operation of the jack.

In order that the ram 23 can be locked in an extended position as indicated in FIG. 4, the jack is provided with an internal ram locking means or ratchet mechanism. This mechanism includes downwardly sloped ratchet teeth 55 formed on two opposed sides of the square main shaft. The teeth, which extend along a major portion of the length of the shaft, are shaped to co-operate with ratchet dog plates or arms 56 and 57. As shown most clearly in FIGS. 4 and 5, each dog plate or arm is substantially the same width as the shaft, and is rotatably mounted on a lock base 58 by curved arms 59 which are received in an aperture 60 in each dog plate. The lock base, which may be formed in two semi-circular sections, includes a square central aperture 61 which is slightly larger in width than the main shaft and is secured to the top of the ram by depending arms 62, the ends of which are received in a groove 63 formed in the outer surface of the ram. An annular locking washer, such as designated by reference numeral 64, may also be provided to assist in fastening the lock plate and ram together. The dog plates are urged into ratcheting engagement with teeth 55 by a surrounding garter spring 65 which abuts posts 66 located at each side of each dog plate or arm.

In order that the dog plates 56 and 57 can be biased out of engagement with the teeth to allow the ram to be returned to its retracted position by compression spring 40, the internal ram locking mechanism further includes straps 70 and 71 which are loosely hung adjacent the

opposed flat sides of the main shaft 24. Referring to FIGS. 7, 8 and 9, these straps are shown to depend from a lock release 72 which has a U-shaped bottom portion with bifurcated legs 73 surrounding the main shaft and an attached bar 74 projecting upwardly through the shaft head 49. The straps 70 and 71 are provided with flanges 75 at their upper ends, the flanges being received between the bifurcated legs 73 so that upward and downward movement of the lock release will produce corresponding movement of the straps relative to the main shaft. Each strap further includes a diagonal cam slot 76 at each end thereof, the slot in strap 70 being formed crosswise of the slot in strap 71 as indicated in FIG. 9. Pins 77 extending from the sides of the main shaft are received 10 within the cam slots 76 whereby vertical movement of the lock release 72 will cause the straps 70 and 71 to move laterally across the sides of the main shaft in opposite directions by action of the pins riding in the cam slots. Lateral movement of the straps in one direction 20 will press the strap 70 into engagement with a laterally projecting leg 78 connected to one side of dog plate 56, and strap 71 into engagement with a leg 79 connected to dog plate 57, thereby pushing the dogs out of engagement with the teeth. Legs 80 and 81 joined to the sides 25 of the dogs 56 and 57, respectively, and disposed on the sides thereof opposite legs 78 and 79, serve to prevent the dogs from laterally shifting out of engagement with the teeth. From this description, it will be apparent that the teeth could be formed on only one side of the main shaft instead of two, and the dog plates could be slidably mounted on the top of the ram 23 for movement and away from the teeth instead of being pivotally mounted.

The pump cylinder 25 is received within the square bore of the main shaft and extends through the shaft head 45 as indicated in FIGS. 3 and 4. The top of the pump cylinder is connected to a plate 90 while a hollow valve seat 92 is joined to the bottom of the cylinder. The upper end of the cylinder is additionally surrounded by a sleeve 93 which is threadedly engaged at one end with the shaft head 45 and integrally joined to plate 90 at the other end. When assembled, the valve seat 92 is normally received in the mouth of a fluid passageway 54 which extends through the shaft base 50. The hollow valve seat together with a spring pressed ball 94, held in passageway 54 by a perforate retaining washer 95, constitute a check valve 96 which permits hydraulic fluid to flow down through the passageway but prevents fluid from flowing in the opposite direction.

The pump piston 26 is slidably received within the pump cylinder and extends through and above plate 90 at the upper end thereof. The bottom end of piston 26 is hollowed out to form a fluid feeding chamber 100 having an enlarged lower end 101 in which is positioned a ball 102 held by a perforate retaining washer 103. Ball 102 constitutes another check valve which, when seated against shoulder 104 during a downstroke of the piston, prevents fluid from entering chamber 100 through the open lower end of the piston. The outer surface of the piston is relieved at 107 in the region of chamber 100 to form, in conjunction with ports 105 and 106 in the main shaft and cylinder, respectively, and ports 108 in the piston, a fluid flow path whereby fluid contained within the outer shell 21 is at all times in communication with fluid in the fluid feeding chamber 100 and is permitted to flow through the chamber 100 while the piston is being raised. O-rings 109 mounted in grooves in the sides of the piston 26 prevent fluid from leaking from the relieved area.

Piston 26 is raised and lowered by actuation of the pump handle 28. As indicated in FIGS. 2 and 3, the handle 28 is channel shaped and has one end rotatably connected to an end of link 121, the other end of the link being pivotally connected to a collar 122 surrounding the outer shell 21. The legs 123 of the channel-

shaped handle may be crimped inwardly in an area generally designated by reference numeral 124, and fitted into engagement with a neck 125 on the top end of piston 26. When assembled in the manner illustrated in FIG. 2, the handle may be moved laterally with respect to the axis of the piston thereby providing a lever arrangement having a mechanical advantage that can be varied as desired. Also, the collar 122 can be rotated with respect to the shell 21 by loosening bolt 126 in order to change the pumping position of the handle. When not in use, the crimped area of the flanges 123 may be disengaged from the piston neck, and the handle thrown over the top of the jack so that it depends vertically along the side of the shell, this position being shown in FIG. 2 in dot-dash outline.

When it is desired to operate the jack, the operator first pushes down the foot pad 27 until it contacts the ground, thereby drawing the ram 23 downward in the shell 21. As the ram is extended below the shell, there is formed between the ram base 41 and the shaft base 50 the pressure area 67. This area is promptly flooded by hydraulic fluid which passes through the fluid ports 105 and 106 into the cylinder area 107, and then into the feeding chamber 100 through ports 108. Check valves 102 and 96 permit fluid in the chamber 100 to flow through passageway 54 into the pressure area. It is possible, of course, to initially extend the ram by reciprocating the piston 26, however, this procedure requires more time than to simply push down on the foot pad.

The ram is automatically locked in the extended position by the dogs or arms 56 and 57 which engage the teeth 55 on the main shaft 24. This locking engagement is permitted when the lock release 72 is in an up position with the pins 77 in the bottoms of the respective cam slots. When in this position, the straps 70 and 71 will be out of contact with the dog actuating legs 78 and 79, respectively, allowing the spring 65 to bias the dogs inwardly.

With the ram extended, the operator then engages the pump handle 28 with the piston 26, and adjusts the handle and the collar 122 to obtain the optimum mechanical advantage and pumping position. As the handle is oscillated to actuate the piston, fluid between the check valves 102 and 94 will be forced by downward movement of the piston past the check valve 94 into the pressure area 67 to further extend and pressurize the ram. It will be apparent that, during the upstroke of the piston, the check valve 94 will seat to prevent hydraulic fluid from leaving the pressure area 67 and valve 102 will open to fill the space between the valves 94 and 102.

When the ram is to be retracted, the operator first pushes down on the lock release 72. This causes the straps 70 and 71 to move vertically with respect to the stationary main shaft. As indicated in FIG. 9, the resulting relative movement of pins 77 in the cam groove shifts the straps laterally, whereby strap 70 contacts leg 78 to push 56 away from the teeth 55 on one side of main shaft 24, and strap 71 contacts leg 79 to push dog 57 away from the teeth on the opposite side of the main shaft.

With the internal locking mechanism thus disengaged, the operator next turns plate 90 to raise the attached cylinder 25 and valve seat 92 away from the shaft base 50 to the position shown in FIG. 6. In this position the check valves 94 and 102 are by-passed and fluid is free to pass from the pressure area 67 into the space between the pump cylinder 25 and main shaft 24, and thence through ports 105. At the same time the ram is automatically fully retracted under action of spring 40.

As the ram retracts under spring action, the dog plates 56 and 57 will come into contact with the lock release 72 and will push the release upwardly to the position shown in FIG. 3. Movement of the lock release pulls along the straps and again causes relative movement of the

pins 77 in the cam slots toward the bottom of the slots. This movement shifts strap 70 to the left and strap 71 to the right, as viewed in FIG. 6, whereupon the dogs 56 and 57 are permitted to again engage the teeth preparatory to another operation. The valve seat 92 may then be moved back into the mouth of passageway 54 by reverse rotation of the plate 90. Alternatively, the by-pass may be kept open until the pressure area is again flooded, and then re-seated.

There is shown in FIGS. 10 and 11 a modified form of my novel leveling jack in which the internal locking mechanism is in the form of a ratcheting, scissors-type gripping means which co-operates with teeth on the main shaft to hold the ram in an extended position.

The principal components of the jack shown in FIGS. 10 and 11 are essentially the same as described in connection with the construction of FIGS. 1 through 9, there being an outer shell 21, a ram 23, a main shaft 24a, a cylinder 25, and a piston 26. The ram is urged toward a retracted position by a compression spring 40, while the piston is actuated by a pump handle 28.

In this embodiment, however, the main shaft 24a is in the form of a hollow cylinder instead of being a square shaft with a square bore, there being teeth 140 on the periphery of the shaft 24a extending along a major portion of its length.

The internal locking mechanism includes arms 141 and 142 pivotally mounted in a scissors-type arrangement by pivot 143 on a lock base 144, the lock base being integrally joined to the top of ram 23. As most clearly shown in FIG. 11, the arms 141 and 142 encompass the main shaft, and, when closed by springs 145 which are fastened to the free end of each arm, co-operate with circumferential teeth 140 to hold or lock the ram in a fixed position.

The pivotally connected ends of arms 141 and 142 are provided with ears 147 and 146, respectively. A release rod 148 having a release handle 149 on its upper end, is rotatably mounted in the shaft head 45 and extends between the ears in a direction parallel to the main shaft, while suitable means (not shown) are provided for rotatably mounting the lower end of the release rod at the bottom of the jack. As shown, the release rod is of square cross-section between the shaft head and the bottom of the jack, however, it may have various other shapes as long as they have unequal radial dimensions for camming the arms 141 and 142 apart against the action of the springs 145 when the release rod is rotated through an angle about its axis.

In operation, the ram is extended by the operator as in the previously described embodiment, the arms 141 and 142 serving to prevent upward movement of the ram under action of spring 145. When the ram is to be retracted, the operator has only to turn the release handle 149 on the rod 148. The twisting of the release rod serves to cam the ears apart and to thereby separate the arms and move them radially out of contact with the teeth 140. Once the arms and teeth are disengaged, the spring 40 will retract the ram, at which time the rod may again be turned to its first position so that the arms will re-engage the teeth under the action of spring 145.

The scissors-type internal locking mechanism is particularly suitable to be incorporated into an aircraft tripod jack, and this arrangement is shown in FIGS. 12, 13 and 14. In the illustrated embodiment, reference numeral 150 designates the legs of jack, the legs being attached to their upper ends to a collar 151 which is connected to an outer shell 152 of the lifting mechanism. The bottom 65 of the shell 152 and a hand pump assembly 153 are mounted on a bottom plate 154, which is attached to each leg 150 as shown.

A ram 160 is reciprocally mounted within the outer shell, and is spaced a short distance inwardly from the 75 inner wall thereof by internal rings 161 and 162. The

ring 161 is secured to the inner surface of shell 152, while ring 162 is carried by the ram.

A cylindrical main shaft 164, having an annular shaft head 165 and a shaft base 166, is positioned within the ram and is secured to the ram for movement therewith by means of a locking ring 167 which locks the flange 168 of the shaft head 165 to the upper end of the ram. As indicated in FIG. 13, the ram and main shaft are spaced apart by a flange 168 on the shaft head 165, and this space constitutes a fluid reservoir 169 which may be filled with hydraulic fluid through the filler plug 170. The main shaft assembly further includes a screw extension shaft 181 which is received within the main shaft and which is threadedly engaged with the interior bore of the shaft head 165.

The shaft base 166 abuts a pedestal 171 when the ram is retracted, and is separated therefrom to form a pressure zone when the ram is extended. Hydraulic fluid is drawn from the reservoir 169 by the hand pump assembly 153 through a passageway (not shown) in the bottom plate 154 and is injected by the pump into the pressure zone 154 and is injected by the pump into the pressure zone through a bore 172 in the plate 154 and a port 173 in the pedestal 171.

A sleeve 182 is fixedly mounted in the reservoir area 169, the bottom of the sleeve being fastened to the sides of pedestal 171. The scissors-type locking mechanism comprising arms 174 and 175 on a lock base 183 is mounted on the top of the sleeve for co-operation with teeth 176 formed on the main shaft 164. As in the previously described embodiment, the scissors arms are biased inwardly by springs 177 attached to the free ends of the arms, while ears 179 and 178 on arms 174 and 175, respectively, co-operate with a release rod 180. The release rod projects downwardly through the bottom plate 154 and has a release handle secured thereto.

The jack may be operatively extended by pumping hydraulic fluid, by means of the hand pump assembly 153, from the reservoir through the bore 172 and port 173 to cause the shaft base and pedestal to separate. Continued expression of fluid into the pressure zone therebetween continues to lift the main shaft and to extend the attached ram. The arms 174 and 175 will grip the teeth on the main shaft to hold the same in a raised position, thus locking the ram in an extended position as shown in dot-dash outline in FIG. 12. The screw extension may also be threaded upwardly to provide increased height if such is desired.

When the ram is to be retracted, the operator twists the release rod 180 to separate and disengage the arms 174 and 175 from the teeth. The ram and main shaft will then fall back into the cylinder until the shaft base again abuts the pedestal.

Obviously many other modifications and variations of the specific forms of the invention shown and described herein are possible in the light of the above teachings. It is therefore to be understood that, within the scope of the appended claims, the invention may be practiced otherwise than as specifically shown and described.

What is claimed is:

1. A jack mechanism comprising an outer shell, a hollow, extensible ram telescopically mounted in one end of said shell, said shell and said ram defining a substantially closed fluid reservoir, means defining a pressure chamber within said hollow ram for hydraulically moving said ram, and a ratchet-type internal locking means within said reservoir for locking said ram in an extended position, said internal locking means including two components relatively movable along the longitudinal axis of said shell, first means connecting a first one of said components to said ram, second means connecting a second one of said components to said shell, means for moving said components into co-operative engagement to lock said ram in a fixed position relative to the shell, a lock release slidably mounted through one end of said shell

and extending into said fluid reservoir, strap means hanging from said lock release, a diagonal cam slot in said strap means, pin means fastened to said second means and extending through said cam slot whereby vertical movement of said lock release will cause said strap means to move toward and away from said first one of said components, a laterally extending leg on said first one of said components, said leg being engageable with said strap means upon movement of said strap means toward the first one of said components to force the first one of said components away from said second means thereby unlocking said ram to permit said ram to be moved relative to the shell.

2. A jack mechanism comprising an outer shell, a hollow, extensible ram telescopically mounted in one end of said shell, said shell and said ram defining a substantially closed fluid reservoir, means defining a pressure chamber within said hollow ram for hydraulically extending said ram, internal locking means within said reservoir releasably connecting said ram and shell for locking said ram in an extended position relative to the shell, said internal locking means including a main shaft having teeth formed on the peripheral surface thereof, said main shaft being disposed within said ram, an arm movably mounted on a lock base surrounding said main shaft, said arm and lock base being relatively movable with respect to said teeth along the longitudinal axis of said main shaft, a tooth engaging surface on one end of said arm, first means for yieldably moving said surface of the arm into engagement with said teeth to lock said arm and main shaft against said relative movement, second means for positively moving said surface of the arm out of engagement with said teeth to permit said relative movement, said second means comprising a lock release slidably mounted on said main shaft, strap means hanging from said lock release, a diagonal cam slot in said strap means, pin means fastened to the main shaft and extending through said cam slot whereby vertical movement of said lock release will cause said strap means to move toward and away from said arm, a laterally extending leg on said arm, each leg being engageable with said strap means when the strap means is moved toward the arm to force the arm away from said main shaft thereby unlocking said ram for retraction, means connecting said main shaft and lock base, respectively, one to said shell and the other to said ram, and a spring connected to said ram for automatically retracting said ram when the surface of the arm is out of engagement with said teeth.

3. In a jack mechanism having an outer shell and an extensible ram telescopically mounted within said shell, said shell and said ram defining a substantially closed fluid reservoir, the improvement consisting of an internal locking mechanism within said reservoir for releasably locking said ram in a fixed position relative to said shell, said locking mechanism comprising a first component fixedly mounted with respect to said ram, a second component fixedly mounted with respect to said shell, spring means for urging said components into locking engagement, a lock release slidably mounted through one end of said shell and extending into said fluid reservoir, strap means hanging from said lock release, a diagonal cam slot in said strap means, pin means fixedly mounted with respect to said shell and extending through said cam slot whereby vertical movement of said lock release will cause said strap means to move toward and away from said first component, a laterally extending leg on said first component, said leg being engageable with said strap means upon movement of said strap means toward said first component to force said first component away from said second component thereby unlocking said ram for retraction, and spring means connected to said ram for automatically retracting it when said components are out of locking engagement.

4. A jack mechanism comprising an outer shell, an extensible ram telescopically mounted within said shell, a

main shaft fixedly mounted within said shell, said shell, ram, and shaft defining a substantially closed fluid reservoir, pressure means for extending said ram, internal locking means within said reservoir for releasably locking said ram in an extended position, said internal locking means including teeth formed on the peripheral surface of said main shaft, an arm having a teeth engaging surface movably mounted on said ram, means attached to said arm for yieldably moving the teeth engaging surface of the arm into engagement with said teeth, a lock release slidably mounted on said main shaft, strap means hanging from said lock release, a diagonal cam slot in said strap means, pin means fastened to the main shaft and extending through said cam slot whereby vertical movement of said lock release will cause said strap means to move toward and away from said arm, a laterally extending leg on said arm, each leg being engageable with said strap means when the strap means is moved toward the arm to force the arm away from said main shaft thereby unlocking said ram for retraction.

5. A jack mechanism as claimed in claim 4 including spring biasing means operatively connected to said ram and shell for automatically retracting said ram when said teeth engaging surface is out of engagement with said teeth.

6. A jack mechanism comprising an outer shell, an extensible, hollow ram concentrically mounted within said shell, a main shaft mounted within said ram, said main shaft being fixedly secured to said shell, said shell, ram, and shaft defining a substantially closed fluid reservoir, means defining a pressure chamber within said hollow ram for hydraulically extending said ram, and internal locking means within said reservoir for locking said ram in an extended position, said internal locking means including teeth formed on the peripheral surface of said main shaft, a pair of arms pivotally mounted on said ram, said arms having teeth engaging surfaces located on opposite sides of said shaft, spring means surrounding said arms whereby said teeth engaging surfaces are yieldably urged into co-operative engagement with said teeth, a lock release slidably mounted on said main shaft, a pair of straps hanging from said lock release adjacent opposite sides of said main shaft, a diagonal cam slot in each strap, the cam slot in one strap being formed crosswise of the cam slot in the other strap, a pair of pins fastened to the main shaft and extending through said cam slots whereby vertical movement of said lock release will cause said straps to move toward and away from said arms, a laterally extending leg on each arm, each leg being engageable with one of said straps when the straps are moved toward the arms to force the arms away from said main shaft thereby unlocking said ram for retraction.

7. The jack mechanism as claimed in claim 6 including spring biasing means operatively connected to said ram and shell for automatically retracting said ram when said teeth engaging surfaces are out of engagement with said teeth.

8. A hydraulic jack mechanism comprising an outer shell, an extensible, hollow ram telescopically mounted in one end of said shell, a ram base closing off one end of said ram, a fluid reservoir in said shell, fluid connecting means between said reservoir and the inner face of said ram base, a fluid pressurizing means in said fluid connecting means for drawing fluid from said reservoir and forcing it against the ram base thereby extending said ram, internal locking means within said reservoir for locking said ram in an extended position, said internal locking means including two components relatively movable along longitudinal axis of said shell, first means connecting a first one of said components to said ram, second means connecting a second one of said components to said shell, means for moving said components into co-operative engagement to lock said ram in a fixed position relative to the shell, a release slidably mounted

15 through one end of said shell and extending into said fluid reservoir, strap means hanging from said lock release, a diagonal cam slot in said strap means, pin means fastened to said second means and extending through said cam slot whereby vertical movement of said lock release will cause said strap means to move toward and away from said first one of said components, a laterally extending leg on said first one of said components, said leg being engageable with said strap means upon movement of said strap means toward the first one of said components to force the first one of said components away from said second means thereby unlocking said ram to permit said ram to be moved relative to the shell, and spring means connected to said ram for automatically retracting the ram when the components have been moved out of co-operative engagement.

9. A hydraulic jack mechanism comprising an outer shell, an extensible hollow ram reciprocally telescoped in one end of said shell, said ram being closed at one end by a ram base, a hollow shaft mounted in said ram, an annular shaft head fastened to the shaft and to the shell at the other end of the shell, a shaft base on said shaft, said outer shell, shaft head, and shaft base defining a fluid reservoir, said shaft base being slidably received against

20 the inner wall surface of said ram, a fluid passageway through said shaft base, a cylinder within said main shaft, a piston reciprocally mounted in said cylinder, the top of said piston extending through the center of said shaft head, a pump handle on the top of the piston, a fluid feeding chamber in the bottom of said piston, an open fluid path between said feeding chamber and reservoir, an outlet from said feeding chamber, a first one-way check valve in said outlet, said first check valve permitting fluid to flow through said feeding chamber and flood

25 said cylinder during the upstroke of the piston, a fluid outlet from said cylinder communicating with said fluid passageway of the shaft base, a second one-way check valve in said fluid outlet from said cylinder, said second check valve permitting fluid to be expressed from said cylinder during the downstroke of said piston to force said ram base away from said shaft base, and thereby extend said ram, a fluid by-pass around said check valves whereby fluid can be expressed from between said shaft base and ram base into said reservoir so that said ram can be retracted, internal locking means within said reservoir for locking said ram in an extended position, said internal locking means including teeth formed on the peripheral surface of said main shaft, a pair of arms pivotally mounted on said ram, said arms having teeth

30 engaging surfaces located on opposite sides of said shaft, spring means surrounding said arms whereby said teeth engaging surfaces are yieldably urged into co-operative engagement with said teeth, a lock release slidably mounted on said main shaft, a pair of straps hanging from said lock release adjacent opposite sides of said main shaft, a diagonal cam slot in each strap, the cam slot in one strap being formed crosswise of the cam slot in the other strap, a pair of pins fastened to the main shaft and extending through said cam slots whereby vertical movement of said lock release will cause said straps to move toward and away from said arms, a laterally extending leg on each arm, each leg being engageable with one of said straps when the straps are moved toward the arms to force the arms away from said main shaft thereby unlocking said ram for retraction, and spring means connected to said ram for automatically retracting the ram when the teeth engaging surfaces of said ram are out of contact with said teeth.

10. A jacket mechanism comprising an outer shell, an extensible hollow ram concentrically mounted within said shell, a main shaft mounted within said ram, said main shaft being fixedly secured to said shell, pressure means for extending said ram, internal locking means for locking said ram in an extended position, said internal locking means including teeth formed on the peripheral surface

of said main shaft, an arm pivotally mounted on said ram at opposite sides of said shaft, spring means surrounding said arms to yieldably urge said arms into co-operative engagement with said teeth, a lock release slidably mounted on said main shaft, a pair of straps hanging from said lock release adjacent opposite sides of said main shaft, a diagonal cam slot in each strap, the cam slot in one strap being formed crosswise of the cam slot in the other strap, a pair of pins fastened to the main shaft and extending through said cam slots whereby vertical movement of said lock release will cause said straps to move toward and away from said arms, a laterally extending leg on each arm, each leg being engageable with one of said straps where the straps are moved toward the arms to force the arms away from said main shaft thereby unlatching said ram for retraction, and spring means connected to said ram for automatically retracting it when the ram has been unlocked.

11. A hydraulic jack mechanism comprising an outer shell, an extensible hollow ram reciprocally telescoped in one end of said shell, said ram being closed at one end by a ram base, a hollow shaft mounted in said ram, an annular shaft head fastened to the shaft and to the shell at the other end of the shell, a shaft base on said shaft, said outer shell, shaft head and shaft base defining a fluid reservoir, said shaft base being slidably received against the inner wall surface of said ram, a fluid passageway through said shaft base, a cylinder within said main shaft, a piston reciprocally mounted in said cylinder, the top of said piston extending through the center of said shaft head, a pump handle on the top of the piston, a fluid feeding chamber in the bottom of said piston, an open fluid path between said feeding chamber and reservoir, an outlet from said feeding chamber, a first one-way check valve in said outlet, said first check valve permitting fluid to flow through said feeding chamber and flood said cylinder during the upstroke of the piston, a fluid outlet from said cylinder communicating with said fluid passageway of the shaft base, a second one-way check valve in said fluid outlet from said cylinder, said second
